BUCKLE.

1,098,086.

Specification of Letters Patent

Patented May 26, 1914.

Application filed January 2, 1914. Serial No. 809,830.

To all whom it may concern:

Be it known that we, HERMAN BLUM and GEORGE E. PRENTICE, citizens of the United States, residents, respectively, of Philadelphia, county of Philadelphia, State of Pennsylvania, and New Britain, county of Hartford, State of Connecticut, have invented a new and useful Buckle, of which the following is a specification.

10 Our invention relates to improvements in buckles for belts or similar devices.

The object is to provide improved means whereby initials, words or other emblems may be interchangeably secured in the frame 15 of the buckle.

The invention comprises improved means for adjusting said initials or emblems in the frame of the buckle and locking the same therein against accidental disengagement; 20 said locking means and letters or emblems being disengageable when it is desired to change the same.

Referring to the drawings, which illustrate, merely by way of example, suitable means for the embodiment of our invention, Figure 1 is a front elevation showing two initials secured in the frame of the buckle. Fig. 2 is an elevation showing three initials properly spaced and secured therein. Fig. 30 3 is a similar view showing a word plate secured in the frame of the buckle. Fig. 4 is a similar view showing an emblem secured in said frame. Fig. 5 is a rear elevation on an enlarged scale with one letter shown secured in place. Fig. 6 is a horizontal section on line 6—6 of Fig. 5. Fig. 7 is a vertical section on line 7—7 of Fig. 5. Fig. 8 is a perspective view of the outer frame of the buckle. Fig. 9 is a perspective view of 40 the inner locking frame. Fig. 10 is a perspective view of a letter adapted to be secured between said frames.

Similar numerals refer to similar parts throughout the several views.

45 Referring to Fig. 5, the under side of the upper horizontal flange 12 of the frame 11 is provided with a series of serrations 13 pressed into the surface of the metal. The lower horizontal flange 14 has a smooth surface. The lugs 15 and 16 project from flanges 12 and 14 toward each other and in a plane substantially parallel with the main body of the frame 11, in the usual manner. The lug 17 is bent over the adjacent exten-

sions of frame 11 and is provided with the 55 pin or post 18 having a head 39 projecting slightly beyond the under surface of lug 17. The inner frame or locking member 19 is provided with the two parallel flanges 20 and 21 which are adapted to fit snugly in the 60 channel between flanges 12 and 14. The cross extensions 22 and 23 are formed by folding the metal upon itself. The recesses 24 and 25 are provided, through one thickness of the metal only, to receive the head 39 65 and forming a detent therewith when the cross-piece 22 or 23, as the case may be, is brought beneath the lug 17. The recesses 26 and 27 are similarly arranged to receive the extension of lug 17. The recesses 28 and 29 70 form bearings for engaging the locking frame 19 when it is desired to dislodge the same from the outer frame 11. The flanges 20 and 21 are provided with the oppositely disposed inclined extensions 30, 31, 32 and 75 33. The various letters, symbols or words are provided with the upper extension 34 having an upper serrated margin 35, corresponding to the serrations 13 of the upper flange 12 of the outer frame 11, and with 80 the lower extension 36 having a plane lower margin as shown in Fig. 10.

The manner of assembling is as follows:— The symbol or letter is placed in the desired position in the frame 11 with the lower margin of extension 36 pressing against the lower flange 14 and against the inner face of the frame. The upper extension is then also moved toward the inner face of the frame, the serrated margin 35 engaging with 85 the serrations 13. The locking frame 19 is then placed in the channel formed between the flanges 12 and 14, with one end projecting slightly out of the end of the outer frame containing the pin 18. The inner frame is then pushed so as to cause the same to slide into position until the inclined surfaces 30 and 31, or 32 and 33, as the case may be, engage beneath the lugs 15 and 16. This forces the frame 19 firmly against the 90 letters and forces the letters in close contact with the inner surface of the frame 11. The cross-piece 22 or 23 as the case may be, is pressed beneath the lug 17 and the recess 24 or 25 as the case may be, engages and locks 95 with the head 39 of pin 18. The parts in such assembled condition are shown in Figs. 5, 6 and 7. An arrow as shown in Fig. 8

may be advantageously marked on the inner side of frame 11 to indicate the direction in which the frame 19 is to be pushed in assembling one frame within the other. The 5 inclined surfaces or lugs 30, 31, 32 and 33 are provided at each end of the flanges 20 and 21 to facilitate convenience in assembling, that is, to make the locking frame 19 reversible. For this reason also the recesses 24 and 25 and 28 and 29 are provided at 10 each end. The purpose of the recesses 28 and 29 is to receive a tool which may rest against the inner side of plate 11 and against the edge or margin of the cross-piece 22 or 15 23 of plate 19. The lower member 36 of the letter or emblem is preferably made of sufficient width to provide a lower margin of sufficient extension to maintain the letter or emblem substantially at right angles with 20 the flange 14 so that when the emblem or letter is placed in the proper position in the frame and then moved in with its serrated margin 35 into engagement with the serrations 13 the letter or emblem will be substantially upright or square with the surrounding frame.

By the use of the term "emblem" in the following claims, we mean to include any display device adapted to be removably engaged in the frame of the buckle; instances 30 of which are given in the drawings.

Two distinct advantages are secured by having the margin of one extension only of the emblem serrated. It prevents the possibility of placing the emblem upside down. 35 It obviates the necessity of placing the emblem primarily in precisely the upright position; since, after assembling the two frames, but before sliding the inner frame into final 40 position, the buckle may be turned over and the smooth end of the emblem may be shifted from left to right as desired, after which the frames are brought into final co-operative position to clamp the emblem there- 45 with.

What we claim is:—

1. A frame having parallel flanges, the inner surface of one flange being serrated, a letter or emblem provided with extensions 50 adapted to fit between the flanges, one extension having a serrated margin for engaging with the serrated flange and another extension having a smooth margin for engaging the other flange and means for locking the same against the inner face of the frame.

2. A buckle comprising a frame having oppositely disposed parallel flanges, an emblem adapted to fit between said flanges, 55 said frame and emblem provided with co-operating recesses and projections and a second frame having sliding engagement with the first frame for securing the emblem therebetween, one of said frames having an inclined portion engaging with the other

frame to produce a binding engagement therebetween.

3. The combination of a frame having upper and lower parallel flanges, an emblem adapted to fit between said flanges, the 70 frame and emblem provided with co-operating recess and projection engagement and locking means for maintaining said engagement comprising a sliding member fitting within the flanges of the frame and 75 means for securing a wedging engagement between said member and frame.

4. The combination of a frame having parallel flanges and lugs projecting from said flanges, an emblem adapted to fit between the flanges and a locking member for securing the emblem in position having wedge shaped extensions for engaging beneath the lugs. 80

5. The combination of a frame having parallel flanges and lugs projecting from said flanges at one end thereof, a lug projecting over the inner side of a portion of the frame at the opposite end thereof and provided with a detent, an emblem adapted 90 to fit between the flanges, a locking member for securing the emblem in position adapted to slide between the flanges of the frame having inclined surfaces for engaging beneath the lugs at one end of the frame, and 95 a recessed part for engaging beneath the detent at the other end.

6. The combination of a frame having parallel flanges, lugs extending from the flanges at one end, a lug extending over a 100 portion of the inner side of the frame at the other end thereof, an emblem adapted to be secured between the flanges against the inner face of the frame and a locking member for engaging the emblem provided with a pair 105 of inclined extensions at each end, either pair adapted to engage the lugs.

7. The combination of a frame having parallel flanges, lugs extending from the flanges at one end, a lug extending over a 110 portion of the inner side of the frame at the other end thereof, an emblem adapted to be secured between the flanges against the inner face of the frame and a locking member for engaging the emblem provided with a pair 115 of inclined extensions at each end, either pair adapted to engage the lugs, said locking member provided with a recess for receiving a tool for disengaging the same from its locking position.

8. The combination of a frame having parallel flanges, lugs extending from the flanges at one end, a lug extending over a portion of the inner side of the frame at the other end thereof, an emblem adapted to be 125 secured between the flanges against the inner face of the frame and a locking member for engaging the emblem provided with a pair of inclined extensions at each end, either of said pairs adapted to engage the lugs, and 130

means for securing locking engagement between the locking frame and the lug at the other end of the frame.

9. A buckle comprising two frame elements having sliding engagement with each other, one of said frames having an inclined portion engaging with the other frame to produce a binding engagement therebetween, an emblem adapted to be associated with said elements, said emblem and one of said frame elements provided with coöperating recesses and projections for securing the relative position of the emblem with said element, said frame elements coöperating in maintaining the emblem in position with respect thereto.
10. A buckle comprising two frame elements having sliding engagement with each other, one of said frames having an inclined

portion engaging with the other frame to 20 produce a binding engagement therebetween, an emblem adapted to be associated with said elements, said emblem and one of said frame elements provided with coöperating recesses and projections for securing the 25 relative position of the emblem with said element, and a detent for normally maintaining the coöperative relationship of said frame elements.
